CHARLES J. WOERNER, OF HAMMOND, AND AMOS M. HUNT, OF GIBSON, INDIANA.

AUTOMATIC OIL-CUP.

1,157,354.

Specification of Letters Patent. Patented Oct. 19, 1915.

Application filed January 29, 1914. Serial No. 815,265.

To all whom it may concern:

Be it known that we, CHARLES J. WOERNER and AMOS M. HUNT, citizens of the United States, residing at Hammond and Gibson, respectively, county of Lake, State of Indiana, have invented a certain new and useful Improvement in Automatic Oil-Cups, and declare the following to be a full, clear, and exact description of the same, such as will enable others skilled in the art to which it pertains to make and use the same, reference being had to the accompanying drawings, which form a part of this specification.

Our invention has for its object to produce a simple and novel device for positively feeding oil or other lubricating material in regulated quantities to the cylinder of an engine or air compressor.

The various features of novelty whereby our invention is characterized will herein-after be pointed out with particularity in the claims; but, for a full understanding of our invention and of its object and advantages, reference may be had to the following detailed description taken in connection with the accompanying drawing, wherein:

Figure 1 is a central vertical section through a device arranged in accordance with a preferred form of our invention; Fig. 2 is a section on line 2—2 of Fig. 1; Fig. 3 is a section on a greatly enlarged scale through one of the valves of the device; and Fig. 4 is a section taken approximately on line 4—4 of Fig. 3.

Referring to the drawing, 1 represents an oil cup of any suitable construction, being in the arrangement illustrated, a hollow cylinder open at the top and having a bottom wall, 2, located a short distance within the lower end thereof. The top of the cup is closed by means of a cap, 3, which in turn may be provided with a detachable plug, 4, through which the cup may be filled. The cup is screwed at its lower end upon a suitable plug, 5, which is in turn adapted to be screwed into the wall of a cylinder or other chamber to be lubricated. Arranged partly in the bottom of the cup and in the plug 5 are two valve devices. The valve devices may conveniently be made by screwing or otherwise securing into the top of the plug socket members, 6, containing conical seats, 7, upon which rest suitable ball valves, 8 and 9, respectively. A passage, 10, extending upwardly through the center of the plug from the bottom thereof is provided with

branches, 11 and 12, respectively, which are continued into the socket members 6, each opening into one of the seats 7 at the apex of the latter. In the bottom wall of the cup are two sockets, 13 and 14, respectively, registering with the sockets 6 and each provided with a conical seat, facing the seat in the socket underneath the same. Each of the sockets 13 and 14 is provided with a port, indicated at 15 and 16, respectively, extending upwardly through the same from the apex of the valve seat. The valve seats 7 and the seat 17 in the socket 14 are plain cones while the seat 18 in the socket 13 is provided with a series of channels, 19, extending from the top to the bottom. With this arrangement, when the balls 8 and 9 are down they act as check valves to prevent fluids from flowing downwardly past the same. When the ball 9 is up it co-operates with the seat 17 to prevent fluids from rising past it. However, when the ball 8 is up the channels 19 provide passages through which fluids can flow upwardly past the ball.

The sockets 13 and 14, and particularly the latter, are preferably made adjustable, this being conveniently accomplished by screwing them into the bottom wall of the cup; thus permitting the up and down play of the balls and particularly of the ball 9, to be regulated.

In using the cup, it is wholly or partially filled with oil or other fluid or fluid-like lubricating material, the plug being screwed into the wall of the cylinder to be lubricated. Assuming that the cup is applied to the air cylinder of an air compressor: It will be seen that on the compression stroke air will flow from the cylinder into the passage 10 and through the branch passages 11 and 12, lifting the ball valves 8 and 9 from their seats. The valve 9, in lifting, closes the port leading upwardly into the oil cup while the channels 19 in the other valve device permit the air to rush past the ball 8 and up into the cup; the air rising through the port 15 and through the oil into the top of the cup where it accumulates and exerts a downward pressure on the lubricant. The air in flowing up past the valve 8 carries with it the lubricant contained in the valve chamber but, since the valve 9 completely closes the port 16 as soon as the valve is lifted, the lubricant in the chamber containing this valve remains and flows down be-

neath the valve. On the suction stroke of the piston the pressure beneath the two valves drops and the valves themselves, assisted by the pressure within the cup, fall or rather are forced into their lower seats, the lubricant contained beneath the valve 9 being forced down into the passage 12 and being drawn into the cylinder. This operation is repeated during each cycle of the 10 compressor piston, although the quantity of air flowing up past the valve 8 is reduced as the pressure in the cup rises, and a small quantity of oil is positively fed down into the cylinder to be lubricated.

15 We have found that the lubricant is not delivered in the form of a drop but leaves the lower end of the plug in the form of a milky spray which causes it to be distributed in the cylinder to the best advantage.

20 By making the socket 14 adjustable the lift of the valve 9 may be varied and consequently the amount of lubricant which is pumped downwardly at each suction stroke of the piston may be varied within any desired limits so that the cylinder may be supplied with exactly the right amount of lubricant without wasting the lubricant and without danger that there will be insufficient lubrication.

25 30 Under some conditions oil may possibly be fed past the air valve 8 as well as past the oil valve 9 and it might therefore be possible to effect a fair degree of lubrication with the use of only a single valve; but we prefer to use two valves as it makes the action positive and certain and makes provision for regulating the feed nicely.

35 It will thus be seen that we have provided a simple and compact device which 40 acts as a small positive force pump the capacity of which may be nicely regulated to suit the demand.

45 While we have illustrated and described with particularity only a single preferred form of our invention, we do not desire to be limited to the exact structural details thus illustrated and described, but intend to cover all forms and arrangements which fall within the terms employed in the definitions of our invention constituting the appended claims.

50 We claim:

55 1. A closed oil cup having formed in the bottom thereof two communicating passages leading to a discharge point of the cup, the upper ends of said passages being in the form of valve seats, ball valves resting on said seats, retaining plugs fitted into the bottom of the cup above said ball valves, each 60 of said retaining plugs having a passage extending through the same from the bottom to a point within the oil cup, the parts being so constructed and arranged that when the ball valves rise one of them closes the 65 passage in its retainer while the other leaves

the passage in the corresponding retainer open.

2. A closed oil cup having in the bottom two communicating ports leading to a discharge point of the cup, there being valve seats surrounding said ports, valves resting upon said seats, a retainer for one of the valves constructed and arranged to permit a limited movement of the valve away from its seat and open communication between the corresponding port and the interior of the cup, and a retainer for the other valve having therein a passage communicating with the interior of the cup and adapted to be closed by the corresponding valve when the latter is raised.

3. An inclosed oil cup having in one side two communicating ports leading to a discharge point of the cup, there being conical valve seats surrounding said ports, balls resting upon said seats, a retainer for one of said balls constructed and arranged to permit a limited movement of the ball away from its seat and open communication between the corresponding port and the interior of the cup, and a retainer for the other ball provided with a seat for the ball and a port leading from said seat into the interior of the cup.

4. An inclosed oil cup having in one side two communicating ports leading to a discharge point of the cup, there being conical valve seats surrounding said ports, balls resting upon said seats, a retainer for one of said balls constructed and arranged to permit a limited movement of the ball away from its seat and open communication between the corresponding port and the interior of the cup, and an adjustable retainer for the other ball provided with a seat for the ball and a port leading from said seat into the interior of the cup.

5. An inclosed oil cup having in one side two communicating ports leading to a discharge point of the cup, there being conical valve seats surrounding said ports, balls resting upon said seats, a retainer for one of said balls constructed and arranged to permit a limited movement of the ball away from its seat and open communication between the corresponding port and the interior of the cup, and a retainer for the other ball arranged in the form of a housing having a seat adjustable from and toward the other seat with which that ball cooperates and having also a port leading from the seat into the interior of the cup.

6. An inclosed oil cup having two valve chambers and a common discharge passage communicating with said chambers, a ball valve in each of said chambers, each adapted to close communication between its chamber and the discharge passage in one of its positions, each of said chambers being provided with an adjustable part containing a

valve seat and a port leading from the valve seat into the interior of the cup, one of said valve seats having grooves therein to provide a restricted passage between the corresponding valve chamber and the interior of the cup when the valve is pressed against the seat.

7. An inclosed oil cup having in one side two communicating ports leading to a discharge point of the cup, there being conical valve seats surrounding said ports, balls resting upon said seats, and closing housings for said balls constructed and arranged to permit a limited movement of the balls from the aforesaid seats, each of said housings having a port leading into the interior of the cup and a conical valve seat surrounding the port, and the valve seat in one of the housings having grooves serving as a by-pass around the ball when the ball is resting against that seat.

8. An inclosed oil cup having in one side

two valve chambers provided with communicating ports leading to a discharge point in the cup, there being conical valve seats 25 in the bottoms of the chambers surrounding said ports, balls resting upon said seats, plugs screwed into the upper ends of said chambers to limit the movements of the balls away from the aforesaid seats, each plug 30 having a conical valve seat and a port leading therefrom into the interior of the cup and there being a restricted by-pass between one of the valve chambers and the interior of the cup when the corresponding 35 valve is seated against the plug forming the closure for that chamber.

In testimony whereof, we sign this specification in the presence of two witnesses.

CHARLES J. WOERNER.

AMOS M. HUNT.
